Des. 189,902
Patented Mar. 14, 1961

189,902

PLASTIC SHEET MATERIAL

John R. Ellefson, Kennett Square, Pa., assignor to E. I.
du Pont de Nemours and Company, Wilmington, Del.,
a corporation of Delaware

Filed Oct. 12, 1960, Ser. No. 62,460

Term of patent 14 years

(Cl. D87—3)

FIG. 1

FIG. 2

Figure 1 is a plan view of a plastic sheet material showing my new design.

Figure 2 is an enlarged portion of the design shown in Figure 1.

I claim:

The ornamental design for a plastic sheet material, substantially as shown.
